UNITED STATES PATENT OFFICE.

OTTO C. GRAF, OF PITTSBURG, PENNSYLVANIA.

DESIGN FOR A FORK.

SPECIFICATION forming part of Design No. 32,913, dated July 10, 1900.

Application filed June 8, 1900. Serial No. 19,628. Term of patent 14 years.

To all whom it may concern:

Be it known that I, OTTO C. GRAF, a citizen of the United States of America, residing at Pittsburg, in the county of Allegheny and State of Pennsylvania, have invented and produced a certain new and original Design for a Fork, of which the following is a specification, reference being had therein to the accompanying drawing.

o This invention relates to a certain new and novel design for a fork, and has for its object to provide a design for a fork of new and original shape.

As shown in the accompanying drawing, the fork consists of the novel outline and configuration which will be hereinafter fully described and specifically pointed out.

In describing the invention in detail reference is had to the accompanying drawing, o wherein is shown a perspective view of my new and original design for a fork.

Referring to the drawing by reference-numerals, 1 indicates the handle or shank, which

tapers toward and terminates into the curved upper end of the tine portion 2, substantially 25 rectangular in contour, and is formed with a series of elongated openings 3, forming the tines or prongs 4.

The reference-numeral 5 denotes a shield upon the back of the tine portion, and which 30 has its outer and inner face formed in an angular manner.

The reference-numeral 6 denotes a suitable ornamentation upon the outer face of the shield.

Having thus fully described my invention, what I claim as new, and desire to secure by Letters Patent, is—

The design for a fork, substantially as herein shown and described.

In testimony whereof I affix my signature in the presence of two witnesses.

OTTO C. GRAF.

Witnesses:

JOHN NOLAND,
N. L. BOGAN.
